What is claimed is the ornamental design for a coverup bib, as shown and described.

DESCRIPTION

FIG. 1 is a perspective view of a coverup bib showing my new design, illustrated with the lower portion of the bib folded up in a raised position;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a front elevational view thereof; illustrated with the lower portion of the bib unfolded in a lowered position; and, FIG. 9 is a rear elevational view thereof.

The broken lines, shown in FIGS. 1 and 4–7 on the surface of the bib, represent stitching.
